Sam Brewster Scholastic A.Y.
Syrup Patent

The Schedule referred to in these letters Patent and making part of the same
containing a description in the words of the said Sam Brewster himself,
of his improvement in the Churn for making Butter from milk or cream
Do all persons to whom these presents shall come. Be it known that
Sam Brewster of the County of Schenectady and State of New York
have invented a new and useful improvement in the Churn, a full
and accurate description whereof, which machine is as follows --

1. An strong frame of a width to correspond with the inside of
the Churn, and reaching to the bottom, extending also over the Churn
from eight to twelve inches more or less according to the size of the Churn
it to use; about equidistant from the side to the top of the frame there
extends a horizontal shaft from one upright Standard to the other, the end
of this shaft passes through one of the Standards and forms of a crank
or pulley for turning the machine. On this shaft there is formed two
cranks near the inner sides of the upright Standards. These have from
thirteen to fifteen inches sweep, more or less and stand at right angles with
each other. Another shaft similar to the one mentioned above except
that instead of passing through the Standard is affixed and turns in
the Standard from eight to ten inches from the bottom parallel with
the upper shaft --

These shafts or cranks are connected together by two
pinions extending from the upper to the lower cranks and are
attached thereto by turning the upper shaft with a crank or pulley,
the lower shaft rotates accordingly --

These shafts are made of iron or other suitable
material. On the lower shaft is affixed a set of rings or washers made
of wood or other suitable material and of a size corresponding to the
size of the Churn. On the outside of the upright Standards the washers
or pieces are cut out one from each Standard and forming a kind of
plate Standard; these fit closely to the outside of the Churn and by

25601
Sliding with gears or Sheaves for the apparatus firmly to the Chain

The lid (in a round a Circle) may be hinged - Circles with strong
spokes cut transversely to allow the pitmen to pass freely. -

This machine may be turned by hand, 11. Water & one power
in Water & hand I have hereto subjoined my name this twentieth
day of November one thousand Eight hundred and Ninety four.
